L. E. LEYENS

CASTING MACHINE

Filed Oct. 2, 1922.

UNITED STATES PATENT OFFICE.

LOUIS E. LEYENS, OF VICKSBURG, MISSISSIPPI.

CASTING MACHINE.

Application filed October 2, 1922. Serial No. 591,703.

My invention relates to improvements in casting machines, and is particularly concerned with improvements in machines to be used for casting stereotype plates or cuts.

5 The objects of my invention are:

First: to provide a casting machine which will enable the operator to cast plates or cuts at a faster rate than it is possible to do with the machines at present in use;

10 Second: to provide a casting machine which can be initially heated to the necessary temperature for producing good results much quicker than is possible with the casting machines at present in use and which, having once been heated, will maintain the necessary temperature over extended periods of time;

15 Third: to provide a casting machine which can easily and quickly be adjusted to cast either plate-high or type-high plates;

Fourth: to provide a casting machine comprising transversely and longitudinally extending gauge bars and means for easily and quickly adjusting such gauge bars;

20 Fifth: to provide a casting machine for casting plates with depressed margins; and

Finally: to provide a casting machine of the character described which is simple in construction, economical to manufacture and which can be easily operated and transported from place to place.

Other objects will appear as this description progresses, reference being had to the accompanying drawings, in which

35 Figure 1 is a plan view of one embodiment of my improved casting machine;

Figure 2 is a side elevation thereof, the top plate being shown in dotted outline in its raised position;

40 Figures 3 and 4 are end elevations of the front and rear ends, respectively;

Figure 5 is an enlarged sectional detail taken on line 5—5 of Figure 1;

45 Figure 6 is an enlarged sectional detail taken on line 6—6 of Figure 1;

Figure 7 is a perspective view of one of the spacing sleeves; and

50 Figure 8 is an end elevation of part of the machine showing the manner and means by which the top plate is spaced from the bottom plate for casting type-high plates.

Throughout the several views similar reference characters will be used for referring to similar parts, and the several sections are

taken looking in the directions of the small arrows.

Referring to the drawings, my improved casting machine comprises the bottom plate 10, the rear end of which has formed integrally therewith the vertically extending supporting legs 11. Extending rearwardly from each leg 11 is a horizontal supporting leg 12, the purpose of which will be referred to later. Lugs 13 project outwardly from each side of the front end of the bottom plate 10 and support the clamping posts 14, which have the annular enlargements 15 intermediate the ends thereof. These enlargements are received in suitable recesses in the tops of the lugs 13. Sleeves 16 are threaded onto the lower and projecting ends of the clamping posts 14 and form legs for the front end of the casting machine.

Hinge brackets 17 are secured to the rear end of the bottom plate by means of the screws 18, or in any other suitable manner, and each comprises the two spaced bifurcations 19 between which is received the eye 20 on the lower end of the hinge post 21. A pintle 22, extending through the bifurcations and the eye, provides means for hingeing the top plate 23 to the bottom plate, the top plate 23 for this purpose being provided with rearwardly extending eyes 24 for receiving the hinge posts 21. Preferably, these posts are provided with the annular shoulders 25 against which the eyes 24 rest. The plate 23 is rigidly held in place upon the hinge posts by means of the thumb screws 26, which engage the outer threaded ends of the hinge posts, and by means of the spacing sleeves 27, the detailed construction and function of which will be described later on.

A lug 28 projecting upwardly from the rear end of the top plate 23 provides a support for the rearwardly extending leg 29. This leg, in combination with the leg 12, provides means for supporting the casting machine in a vertical position, as will be referred to in the description of the operation of my machine. In the raised position of the top plates (shown in Fig. 2), the leg 29 rests against the lug 29' projecting rearwardly from the bottom plate.

Rotatably mounted upon the clamping posts 14 are sleeves 30 each having an annular shoulder or lug 31 extending from the bottom thereof and a second lug 32 project-

ing from the upper end thereof. The lug 32 does not extend entirely around the sleeve 30. With these lugs turned to the position shown in Figure 3, the bottom of the top plate rests upon the lug or shoulder 31, the thickness of this element being such as properly to space the top plate from the bottom plate for casting plate-high plates. When, however, the sleeves 30 are rotated to position the lugs 32 beneath the top plate, as will be described later on, the two plates are then spaced properly for casting type-high plates.

Mounted upon each of the clamping posts 14, immediately above the sleeves 30, is a second sleeve 33, which carries a clamping bracket 34, the outer end of which is provided with an internally threaded boss 35 for receiving the threaded clamping screw 36, the lower end of which is adapted to engage the top side of the top plate.

The upper ends of the clamping posts 14 are threaded for receiving thumb nuts 37 and between the latter elements and the sleeves 33 are interposed spacing sleeves 38, to be referred to later on.

Brackets 40, secured to and extending upwardly from the top plate, provide means for securing the handle 41 to the top plate.

A rail 42 extends transversely of and is secured to the front end of the bottom plate by means of the posts 43, which project outwardly from the front end of the bottom plate. This rail acts as a support for the sliding shoes 44, which are yieldingly held in any of their adjusted positions upon the rail 42 by means of the bow springs 45 interposed between the bottom of the rail and the bottom of the shoe. The upper sides of the shoes are provided with transversely extending rectangular grooves 46 for receiving the gauge bars 47. These bars are yieldingly held in their adjusted positions by means of the clamping plates 48 which are pivoted to brackets 49 extending upwardly from the shoes, by means of pins 50, and yieldingly held in engagement with the gauge bars by means of the springs 51, which are coiled about the pins 50. The outer ends of these springs engage the lower side of the outer ends of the clamping plates 48 and yieldingly urge them upwards. By means of the construction just described it will be apparent that the gauge bars 47 can be easily and quickly adjusted both longitudinally and transversely of the machine.

For co-acting with the inner ends of the gauge bars 47, I provide the transversely extending gauge bar 52, each end of which is provided with a shoe 53 which slidably engages the adjacent edge of the bottom plate 10. One of the shoes is provided with the thumb piece 54 and the other shoe has a downwardly extending lug 55 (see Figure 5) in which is mounted the set screw 56, one

end of which is adapted to be brought into engagement with the flange 57 extending downwardly from the bottom plate to lock the gauge bar 52 in any of its adjusted positions. The head of the screw 56 may be used for the same purpose as the lug 54, for adjusting the bar 52 longitudinally of the casting machine.

By reference to Figure 6, it will be noted that for casting plate-high plates I provide longitudinal gauge bars 47, one face of which is cut away or beveled adjacent one edge thereof, as shown at 47' in Figure 6 for receiving between it and the bottom plate one edge of the mat 58. The opposite face of the gauge bar is also cut away, as shown at 47" for the purpose of casting a plate having depressed margins through which the nails may pass for securing the plate to its wooden backing, thus bringing the heads of the nails below the printing surface of the plate and preventing the nails from producing black spots during the printing operations. For making type-high plates I prefer to use gauge bars 47^a which are L-shaped in cross section (see Figure 8). I preferably undercut the lower side of the transversely extending gauge bar 52, as shown at 52' in Figure 5 for receiving the edge or margin of the mat.

Some mats are provided with paper extensions (or aprons) which extend outwardly beyond the front ends of the top and bottom plates to prevent metal from running down between the mat and the bottom plate, and to permit these aprons to lie flat along the front edge of the bottom plate, I notch the shoes 44, as shown at 59 (see Figure 3) to receive the edges of the aprons.

I have already referred to the flange 57 extending downwardly from the bottom plate 10. This flange extends entirely around the bottom plate and a similar flange 60 extends upwardly from the top plate. The top plate is also provided with longitudinally and transversely extending intersecting ribs 61 and 62, respectively. The bottom plate is provided with similar ribs which are not shown. One of the functions of these ribs and the flanges 60 is to make it possible to reduce the thickness of the top and bottom plates, but at the same time to hold them rigidly against any tendency to warp or bend under the influence of the heat and pressure to which they are subjected during use.

When my improved casting machine is used for casting plate-high plates, the spacing sleeves 27 and 38 are respectively positioned as shown in Figures 2, 3 and 4, but when it is used for casting type-high plates the positions of the spacing sleeves 38 and the sleeves 33, carrying the clamping brackets 34, are reversed, as shown in Figure 8, and the spacing sleeves 27 are placed be-

tween the eyes 24 and the annular shoulders 25. The thumb screws 26 will then bear directly upon the upper sides of the eyes 24. In casting type-high plates a suitable type-high gauge bar 47^a (see Fig. 8) is used for spacing the top and bottom plates.

For the purpose of facilitating the adjustment of the top plate relatively to the bottom plate, I provide the spacing sleeves 27 and 38 with longitudinally extending slots 63, which permit the removal of the sleeves from the posts 14 and 21 by a lateral movement. For yieldingly holding the sleeves upon these posts I provide the ring-shaped spring 64, which is positioned in the counter-sunk bore 65 in one end of the sleeve and is secured in place by means of a rivet 66, or in any other suitable manner. The ends of this spring are curved outwardly, as shown at 67, to engage the sides of the posts to spring these ends outwardly when the collar is to be replaced upon one of the posts.

In the use of my improved casting machine, a mat is laid upon the bottom plate, which at this time rests upon the legs 11 and 16, and the gauge bars 47 and 52 are adjusted to the sides and bottom of the mat, as shown in Figure 1. The top plate is then closed upon the bottom plate and the brackets swung around to position the screws 36 so as to engage the top of the top plate when they are screwed inwardly, thus clamping the top plate tightly against the gauge bars. The casting machine is then raised to a vertical position and stood upon the legs 12 and 29, whereupon molten metal can be poured between the upper ends of the two plates, the end of the top plate preferably being beveled, as shown at 68, to facilitate this operation. When the metal has solidified, the clamping screws 36 can be released, the upper plate turned back and the plate removed.

While my improved machine can be made of cast iron, or any other similar material, I prefer to make it out of materials having high specific heats and heat conductivities, as I have discovered that by the use of such metals, it is not only possible to quickly bring the casting plates to the proper initial temperature, but that they will remain hot enough over considerable periods of time to enable successive casts to be made without the necessity of again preheating them, and I can obtain these results with casting plates containing very considerably less metal by volume than has heretofore been found necessary. To obtain these results, I have found that aluminum and its alloys, particularly its copper alloys, are very satisfactory. As much as 10% or 15% of copper has been found to provide a satisfactory alloy, although it is to be understood that considerable variations from these percent-

ages may be made without departing from my invention.

Not only does the use of the material specified above expedite the making of plates by cutting down the time initially required for heating the plates and by making it possible to have longer intervals of time between the casting of successive plates, but they also make it possible to more rapidly cast the plates, because I have found that they will abstract the heat from the molten metal much more rapidly than cast iron.

While I have described the details of construction of the preferred embodiment of my invention, it is to be clearly understood that my invention is not limited to these details, but is capable of other adaptations and modifications within the scope of the appended claims.

Having thus described my invention, what I claim is:

1. A casting machine comprising a bottom plate having a clamping post projecting upwardly therefrom at each side of one end and a pair of hinge posts pivotally mounted upon the other end in spaced relation to each other, a top plate having a pair of eyes at one end for receiving said hinge posts, a clamping bracket pivotally mounted upon each of said clamping posts, a clamping device carried by each of said clamping brackets for adjustably engaging said top plate, a spacing sleeve rotatably mounted upon each of said clamping plates, said spacing sleeves having lugs adapted to be positioned to support said top plate, other spacing sleeves mounted upon said clamping posts and hinge posts, said last-mentioned spacing sleeves being slotted to permit their removal from said posts, spring means for yieldingly holding said last-mentioned spacing sleeves on said posts, and adjustable means for securing said sleeves on said posts.

2. A casting machine comprising a bottom plate having a clamping post projecting upwardly therefrom at each side of one end and a pair of hinge posts pivotally mounted upon the other end in spaced relation to each other, a top plate having a pair of eyes at one end for receiving said hinge posts, a clamping bracket pivotally mounted upon each of said clamping posts, a clamping device carried by each of said clamping brackets for adjustably engaging said top plate, a spacing sleeve rotatably mounted upon each of said clamping plates, said spacing sleeves having lugs adapted to be positioned to support said top plate, other spacing sleeves mounted upon said clamping posts and hinge posts, and adjustable means for securing said sleeves on said posts.

3. A casting machine comprising a bottom plate having a clamping post projecting upwardly therefrom at each side of one end and a pair of hinge posts pivotally mounted

upon the other end in spaced relation to each other, a top plate having a pair of eyes at one end for receiving said hinge posts, a clamping bracket pivotally mounted upon each of said clamping posts, a clamping device carried by each of said clamping brackets for adjustably engaging said top plate, spacing sleeves mounted upon said clamping posts and hinge posts, and adjustable means for securing said sleeves on said posts.

4. A casting machine comprising a bottom plate having a clamping post projecting upwardly therefrom at each side of one end and a pair of hinge posts pivotally mounted upon the other end in spaced relation to each other, a top plate having a pair of eyes at one end for receiving said hinge posts, a clamping bracket pivotally mounted upon each of said clamping posts, and spacing sleeves mounted upon said clamping posts and hinge posts.

5. A casting machine comprising a bottom plate having a clamping post projecting upwardly therefrom and a hinge post pivotally mounted upon the other end, a top plate adjustably mounted on said hinge post, and a clamping bracket pivotally mounted upon said clamping post.

36 6. A casting machine comprising a bottom plate having a hinge post pivotally mounted upon one end, and a top plate adjustably mounted on said hinge post.

7. A casting machine comprising a bottom plate, a top plate and means for hinging said top plate on said bottom plate, including means for adjusting the spacing of said top plate relatively to said bottom plate.

8. A casting machine comprising a bottom plate, a rail secured to and extending transversely of one end of said bottom plate, a shoe slidably mounted upon said rail, spring means for yieldingly holding said shoe in any of its adjusted positions, said shoe having a groove extending transversely thereof

for receiving a gauge bar, and means carried by said shoe for yieldingly holding said gauge bar in any of its adjusted positions.

9. A casting machine comprising a bottom plate, a rail secured to and extending transversely of one end of said bottom plate, a shoe slidably mounted upon said rail, means for yieldingly holding said shoe in any of its adjusted positions, said shoe having a groove extending transversely thereof for receiving a gauge bar, and means carried by said shoe for holding said gauge bar in any of its adjusted positions.

10. A casting machine comprising a bottom plate, a gauge bar extending transversely thereof, a shoe secured to each end of said gauge bar, and slidably engaging the adjacent edge of said bottom plate, and adjustable means carried by one of said shoes for securing said gauge bar in any one of its adjusted positions.

11. A casting machine comprising a bottom plate, a gauge bar extending transversely thereof, and a shoe secured to each end of said gauge bar, and slidably engaging the adjacent edge of said bottom plate.

12. A gauge bar for casting machines comprising a bar, the mat side of which is cut away adjacent its edge.

13. A stereotype plate casting machine comprising a bottom plate and a top plate, and means for hinging said top plate upon said bottom plate, said last-named means comprising means for adjusting said top plate relatively to said bottom plate to enable the casting of plates of different thicknesses.

14. A stereotype plate casting machine comprising top and bottom plates made from an alloy, the greater percentage of which is aluminum.

In witness whereof, I hereunto subscribe my name this 26th day of September, 1922.

LOUIS E. LEYENS.
